SIGNALING SYSTEM

Frank R. Bridges, Needham, Mass., assignor to
The Gamewell Company, Newton Upper Falls,
Mass., a corporation of Massachusetts

Application July 2, 1932, Serial No. 620,683

16 Claims. (Cl. 177—367)

This invention relates to signaling systems and more particularly to fire alarm and similar systems which, as is well known, require provisions for reliable operation even under extremely adverse conditions as, for example, broken, grounded, or short circuited lines. Such provisions include in most cases the use of an emergency conductor, which is under certain conditions supplied with current impulses derived from the source normally supplying the signaling circuit with current. The present invention also utilizes a separate conductor, usually the ground, for emergency signaling, but provides improvements which render the operation of signaling systems of this type especially secure and certain.

The primary object of the present invention is to provide a signaling system with an emergency conductor which, under faulty conditions of the system, is supplied with current independently of the normal current supply, the circuit being so arranged that the current for emergency operation is not influenced by the nature of the existing fault, so that the emergency operation is independent of any abnormal conditions which might influence an emergency current source which is in any manner dependent upon, or associated with the normal current source and the normal operation of the system generally.

Other objects are to provide a signaling system using direct current for normal operation and alternating current for emergency operation, or conversely, the effectiveness of the emergency current being independent of the normal current and the nature of the faulty condition which necessitates emergency operation, to provide a signaling system employing normal line current for emergency operation, to provide an unweakened and undistorted alternating current supply for signaling under all emergency conditions, and to provide an emergency power source for a signaling system of the nature referred to whose characteristics, as, for example, the voltage, can be adjusted to conform with prevailing conditions (especially the ground resistance of a given circuit), independently of circuit characteristics which influence the character of the current for normal operation.

A further object is to provide a signaling system employing two distinct current supply and signal reception circuits, one carrying alternating current and the other direct current, and two partly identical signal transmission circuits as, for example, normal and emergency transmission circuits, whereby each supply circuit is exclusively

associated with one of the two transmission circuits.

Still further objects are to provide an improved signaling system with emergency conductor, which permits the installation of simple and effective provisions for connecting reserve power supply means in case of failure of the normal power supply, and to provide a power supply arrangement with provisions of this kind.

In one aspect, the invention provides in its preferred embodiment a signaling system with a normally closed signal line or loop continuously energized with direct current, and an alternating current source also continuously associated with the circuit and in addition with an emergency conductor, usually the ground, permitting the transmission of signals over the latter, and that portion of the normal circuit which remains serviceable. The invention also provides means which keep the two current sources electrically separated, thereby preventing any unfavorable mutual influence. This arrangement permits emergency operation, for example, with current derived from an ordinary public utility line, uninfluenced by any connection with the normal source of signaling current and, in one modification, the constant flow of superposed alternating and direct currents in the outside signal circuit. Normal operation takes place only with direct current acting upon certain signal manifesting devices, whereas alternating current is employed for emergency operation with a different set of manifesting devices. This provides for the possibility of independent adjustment to certain problems which are different for normal and emergency signaling as, for instance, adjustment to impedances which may be quite distinct in both cases. The usefulness of previous systems operating through emergency ground connections is limited mainly by the relatively high resistance of the ground connections. To maintain sufficient current flow through these connections requires voltages which are under normal circuit conditions excessive. By providing two separate current supply sources, one for example a direct current source of a voltage only sufficiently large to maintain current flow through the normal circuit, and a second independent source furnishing alternating current for emergency operation, I am enabled to choose an alternating current voltage sufficiently high to send a satisfactory signaling current through ground connections of relatively high resistance. The general advantages of having an emergency

50

55

supply of full power not derived from a source which is also used for normal signaling and which might be incapacitated just when its proper operation is most desirable, that is, under emergency 5 signaling conditions, are obvious.

As mentioned hereinbefore, the signal transmitting means used in my new circuit may be of any well-known type, provided that they are not only adapted to send signals by interrupting 10 the normal circuit, but also to establish connections to an emergency conductor (usually the ground) and to send signal impulses over this emergency connection. In order to avoid difficulties due to shunt paths under certain circuit 15 conditions, heretofore known systems required special signal transmitting means which make connection to ground only in the event of circuit trouble. The present system does not require direct metallic connections to ground for emergency 20 signaling, in order to provide an emergency signaling circuit of sufficiently low resistance, but permits the use of alarm boxes which ground during each signaling period, whether the circuit is abnormal or not, by establishing 25 ground connections which, however, are only effective for emergency signaling if the circuit is actually abnormal. Alarm boxes of this type operate more effectively with full alternating emergency current than with fluctuating or more 30 or less irregularly alternating emergency current of other systems which derive normal and emergency current from the same source.

As indicated above, the present invention contemplates, generally speaking, a source of current 35 of a certain type, preferably direct current, either for each individual signal circuit, or for several circuits in multiple, and recording devices responding to this current which is employed for signaling under normal conditions. In addition 40 to a second, independent source of a different type of current, preferably ordinary alternating current, is provided for emergency signaling, this source being associated with the emergency conductor and cooperating with signal recorders 45 responsive to this second current. Means as, for example, choke coils and condensers, are further provided for electrically separating the two kinds of supply sources and recorders, as will be described in detail hereinafter.

In another aspect, the new system permits the use of simple but effective provisions for an emergency power supply in case the normal supply, as for instance the public utility system, fails. Since the normal and emergency signaling 55 sources are quite independent in their action, any interlocking or otherwise correlating arrangements between normal and emergency current sources are unnecessary.

In a further aspect the new system is advantageous because existing signaling systems which have no provisions for signaling under the adverse conditions referred to above can be easily changed in conformity with the present invention merely by adding relatively simple and inexpensive parts, so that it is not necessary to discard existing equipment in order to take advantage of the improved arrangements of the invention.

Still further objects, aspects, and advantages of 70 the invention will be apparent from the following detailed description of specific embodiments thereof by way of example. The description refers to drawings, in which;

Fig. 1 is a connection diagram of a fire alarm system incorporating the invention;

Fig. 2 is a similar diagram of a modified embodiment of the invention;

Figs. 3, 4 and 5 are simplified diagrams of a circuit according to Fig. 1 indicating the operation of the new system under various conditions; 5

Figs. 6, 7 and 8 are similar simplified diagrams of a circuit according to Fig. 2;

Fig. 9 is a connection diagram of an embodiment utilizing direct current for emergency operation; and

Fig. 10 is a connection diagram of a fire alarm system according to the present invention, with several signaling circuits and a reserve power supply arrangement.

Referring to Fig. 1, L denotes a signal line or 15 loop leading to station terminals 1 and 2 and containing a number of signal transmitters, herein referred to as alarm boxes M, N, P, R and S which normally keep the signal loop closed and the ground connections open. Busses DC supply direct current of suitable voltage derived from any 20 convenient source, and leads 3 and 4 of the direct current circuit D connect terminals 1 and 2 to these busses. Lead 3 contains an inductance 10 intermediate terminal 1 and its direct current bus, and a signal recorder X is inserted in lead 4 between terminal 2 and the other direct current bus. Although the signal recorders are herein indicated as being of the tape imprinting type, it is understood that any signal manifesting device 30 may be used instead. A battery B, in the nature of a so-called floating reserve power supply, may be connected across leads 3 and 4. Busses AC supply alternating current, preferably from the public utility line, to the primary 11 of a transformer T. One terminal 14 of the transformer secondary 12 is grounded, whereas the other terminal 15 leads to conductor 7, which is part of an alternating current circuit A including lead 5 connected to terminal 1, a capacitance 21, an inductance 23, recorders Z and Y, an inductance 24, a capacitance 22 and lead 6 connecting to terminal 2. Inductances 23 and 24, in series with condensers 21 and 22, are provided for the purpose of compensating the phase displacing effect 45 of the capacitances, in order to decrease as far as possible the impedance of the alternating current circuit.

The direct current derived from busses DC continuously supplies the signal loop L, so long as 50 the latter is not interrupted by the code signal sending means of an alarm box, or by a break in the line. Condensers 21 and 22 prevent direct current from entering circuit A, whereas circuit D is protected from alternating current by choke 55 coil 10 which is so dimensioned that its inductance presents an alternating current resistance of a magnitude excluding for practical purposes the alternating current of A. It will be obvious to any one skilled in the art, that inductance 10 60 passes substantially only direct current and that capacitances 21 and 22 pass substantially only alternating current, so that the loop L may carry superposed direct current and alternating current, whereas alternating current is excluded 65 from circuit D and direct current from circuit A. It is also apparent that in a circuit according to Fig. 1, the loop L carries exclusively direct current, so long as it is not grounded, since the E. M. F. furnished by transformer secondary 12 70 can be applied to L only over ground. However, if the loop is grounded, it carries alternating current corresponding to the E. M. F. supplied by the entire secondary 12.

As pointed out hereinbefore, the alarm boxes 75

in the outer circuit or loop may be of any known type having provisions for forming signals in a normally closed circuit and also facilities for signaling through an emergency conductor, normally the ground. Fig. 1 shows schematically various types of alarm boxes M, N, P, R and S, as representatives of such signal initiating means, and these boxes will now be shortly described as far as their characteristics have a bearing on the 10 operation of the boxes in a circuit according to the present invention.

The alarm box M represents the simplest type of signal transmitters suitable for operation with circuits of this type, and is described in the patent of Clarence E. Beach for "Signal system", No. 1,528,596, dated March 3, 1925. It comprises contacts 61, 62 and 63 actuated by a code wheel 68 in such a manner that under normal inoperative condition of the box contacts 61 and 62 are 20 closed, thereby completing the series signaling circuit, whereas upon operating the box all three contacts 61, 62 and 63 are connected when 61 is lifted by one of the cams of wheel 68, and then again disconnected when 61 descends after having 25 passed over the cam. The opening of all three contacts interrupts the closed circuit for normal signaling, whereas the interconnection of all three contacts intermittently grounds the circuits for emergency signaling, each signal impulse comprising one grounding and one interruption 30 of the normal circuit. A condenser 65 may be connected intermediate contact 63 and ground.

The alarm box N is representative of signal transmitters similar to those described in the patent to Frederick W. Cole for "Successive non-interference signal box", No. 553,838, dated February 4, 1896. This mechanism comprises normally closed contacts 71 for shunting the box circuit at rest, contacts 75 and 76 for normal signaling, and a non-interference magnet 73 which controls contacts 79, windings 73 being connected across contact 71. The non-interference magnet of this box, like the non-interference device of all the other alarm boxes herein discussed, is assumed to be responsive exclusively to direct current. The outside terminals of 73 lead to contacts 75 and 76 respectively, the latter being arranged for interconnection therebetween and with the grounding switch 79 incident to the engagement 50 therewith of the teeth of the code wheel 78. The normally open contact 79 is operable by the box mechanism to establish ground connection. Contacts 75 and 76 are for normal signaling when switch 79 is open. During emergency operation, that is, if the signaling loop should remain open a longer time than the longest break within any signaling period, contacts 79 are closed and each connection between 75 and 76 is accompanied by a connection with ground over 79, whereas if 75 and 76 are disconnected the ground connection is 60 also interrupted. Instead of employing contacts 75 and 76, as shown, a contact arrangement similar to that of box M (contacts 61, 62 and 63) may be incorporated in a box of this type.

Box P is somewhat similar to that disclosed in Patent No. 1,244,587 for "Successive non-interference box" to F. W. Cole, dated October 30, 1917, but has additional means for sending signals over ground. It comprises shunting contacts 81, normally closed signaling contacts 84, 86 and non-interference magnet 85 in series across the box terminals, and normally open contacts 82, 83, adapted to connect the line to ground. Both pairs of contacts may be operated by the 75 code wheel 88 as shown. If one code wheel is

used, an insulating block 87 is arranged intermediate levers 82 and 84, so that lever 82 can move independently of 84, if the latter is retained in raised position by pin 80 associated with the armature of non-interference magnet 85 in such a manner that 80 moves underneath 84 if the armature is deenergized. Normally code signals are sent by contacts 84 and 86 opening and closing in accordance with the code represented by the teeth of wheel 88 whereas, if the line is interrupted due either to a break or the fact that another box is already signaling, magnet 85 is deenergized, its armature drops, and moves pin 80 underneath lever 84, thereby preventing it from breaking contact at 86. In this case, lever 82 continues to cooperate with the code wheel, so that signals can be despatched over ground and a portion of the normal signaling circuit. Preferably, a condenser 89 is arranged in the ground connection. 20

The signal transmitter R has a normally closed shunting switch 70 which opens when the box is pulled and remains open so long as the box movement is operative, namely, so long as the double code wheel 90 rotates, the latter comprising two identical toothed portions on a common shaft and being adapted to actuate two sets of switch levers 96 and 97, 98 and 99 respectively, 96 and 97, and 98 and 99 respectively being interconnected by blocks of insulating material which 30 electrically separate the switch levers but permit their joint operation by the code wheel, which upon rotating lifts and drops levers 97 and 99 in known manner. Spring contacts 91 and 92 are connected to the terminals of a non-interference 35 solenoid 100, operative substantially only with direct current, and also to another pair of spring contacts 93 and 94, respectively, which cooperate with 98 and 99 respectively. Switch levers 98 and 99, herein referred to as grounding contacts, are joined to ground through conductor 95. Under normal, inoperative conditions, the followers of levers 97 and 99 rest on cams 60 of the code wheel, which keep them in elevated position, thereby connecting levers 96 and 97 with 45 contacts 91 and 92, respectively, whereas levers 98 and 99 are lifted from contacts 93 and 94. Pin 50 is associated with the armature of the non-interference magnet 100 and permits free movement of levers 96 and 97, if the non-interference magnet was energized during the initial 50 signaling period of the box, notwithstanding a subsequent deenergization due to the opening of the signaling circuit at 91 and 92 or a subsequently pulled box. A locking arrangement accomplishing this result is, for example, described in the above-identified patent to F. W. Cole. If no current is flowing in the circuit due to previous pulling of another box or to some accident, and non-interference magnet 100 is therefore deenergized upon the opening of 70, the pin 50 moves underneath lever 97 and prevents its dropping and therefore the opening of the circuit at 91 and 92. Therefore, if box R is pulled with the circuit in good condition, as shown in Fig. 1, the circuit remains closed over 96, 91, 100, 92 and 97; 70 is opened, magnet 100 remains energized, pin 50 is out of the way, and the circuit is 60 opened and closed at 91 and 92 when the follower of 97 drops in the interdental spaces of its code wheel, thereby initiating code signals. Shortly after contacts 91, 96 and 92, 97, respectively, open, contacts 93, 98 and 94, 99, respectively, close, and establish a ground connection. The 75

ground connection at 98 and 99 is again interrupted shortly before contact is reestablished at 91 and 92. When box R is sending, and the line is interrupted, as, for example, due to a break 5 in the line, or due to another box already operating, pin 50 prevents levers 96 and 97 from dropping and interrupting the circuit at 91 and 92, whereas levers 98 and 99 are independent of the non-interference magnet and establish ground 10 connections at 93 and 94 every time the follower of 99 passes over the teeth of code wheel 90.

The alarm box S is of the type as described and claimed in the copending application of Clarence E. Beach for Signal apparatus, Serial 15 No. 573,150, filed November 5, 1931, now Patent No. 2,018,656, and comprises a shunting switch 111 normally closed, conjointly operating signal switches 112 actuated by a code wheel 118, non-interference magnet 113 and a grounding switch 20 116 with three contacts as indicated in the drawings. Boxes of this type, as well as boxes of the type N ground the circuit only when emergency conditions prevail, and can therefore be directly grounded, whereas boxes of the types M and P 25 are preferably grounded over condensers. Box R, although grounding during each signaling period, may or may not be provided with grounding condensers.

In the modification according to Fig. 2, only 30 an alternating current supply, indicated by busses AC, is provided. Direct current for supplying loop L with boxes M, N and P is derived from the alternating current busses by means of a rectifier bridge C comprising four terminals 31, 32, 33, 34 and four asymmetric conductors or electric valves 35, 36, 37 and 38. The secondary 42 of transformer 30 is connected across terminals 31 and 32, the transformer primary 41 is supplied from busses AC, and the leads 3, 4 40 of direct current circuit D are connected to terminals 33 and 34. Circuits D and L are otherwise similar to the corresponding parts of Fig. 1, as indicated by the use of like numerals in both figures. Busses AC also supply primary 51 of transformer Q, and terminals 54 and 55 of the secondary 52 are connected to conductors 56 and 57 of the alternating current circuit A. The transformer secondary has an intermediate terminal or tap 48, which is grounded. The alternating current circuit A and the direct current circuit D are again electrically separated by a choke coil 10 and condensers 21, 22, respectively, and a floating reserve battery B and inductances 23, 24 are also provided in this embodiment.

In certain instances, for example if only existing direct current equipment is to be utilized, it may be desirable to employ direct current apparatus in circuit A. As indicated in Fig. 2, this may be accomplished by connecting direct 55 current recorders, or relays U, V and W by means of rectifier bridges 65, 66 and 67. Hence, in the embodiment of Fig. 2, the signaling system may be operated with current derived only from the ordinary alternating current supply, but operate exclusively with direct current apparatus adopted from an existing direct current system which was previously supplied from batteries.

Whereas in the modification according to Fig. 70 1, the source of alternating E. M. F., namely, transformer secondary 12, is connected in parallel with the circuit A, and therefore supplies alternating current only if its second terminal is connected to the signal loop through ground, circuit 75 A of the modification according to Fig. 2 includes

secondary 52 in series and the signal loop therefore carries alternating current continuously. Under normal conditions, and if the signal loop is grounded without being interrupted, the signal loop L carries direct current furnished by rectifier bridge C, and superposed alternating current supplied by the entire secondary 52. Under abnormal conditions, if the loop is interrupted and grounded for emergency signaling, only one-half of the secondary supplies alternating current, as 10 will be explained more in detail hereinafter.

Under normal conditions of the signaling circuit the new system operates as follows: Referring more particularly to Fig. 3, which is a simplified diagram of the circuit according to Fig. 1, if the line is wholly normal and none of the boxes are operated or "pulled", no alternating current flows in any part of the circuit since only one terminal of secondary 12 is connected thereto. Direct current flows in circuits D and L and is excluded from 20 circuit A by condensers 21 and 22 as hereinbefore described. Recorder X is normally energized, whereas recorders Y and Z are deenergized and, upon operation of a box, signals are received at X, recorders Y and Z remaining inoperative. The 25 non-interference arrangements of any type of box operate exactly as in a non-grounded system. However, if the boxes are of the type which keep the signaling circuit closed, but establish ground, and signal over ground each time when the non- 30 interference magnets are deenergized, upon a box being pulled (as for example boxes of type R, referring to the designations of Fig. 1), the signals of two simultaneously sending boxes are received correctly. For example, if box 101 (as 35 assuming it to be of type R) is pulled first and box 102 somewhat later, the direct current signals of 101 are received at X, whereas alternating current circuits a and b are established by box 102 and corresponding signals received at Y and Z. Box 40 102 signals over Y and Z while box 101 operates, whereas upon 101 stopping and releasing the direct current circuit, box 102 assumes control of the direct current circuit and its remaining signals are also received at X.

In the case of a broken circuit, as indicated at c of Fig. 4, the direct current is interrupted, recorder X drops its armature and becomes incapacitated, and, provided that the boxes of the circuit do not ground the same upon deenergization of their non-interference magnets (for example, if the boxes are of type P or R), substantially no current flows in the system. If the circuit should employ boxes which ground the line upon its deenergization, (as for example boxes of type N or S), as indicated in Fig. 4 at d of box 102, alternating current flows through circuit e. If pulled, a box of this type interrupts the ground connection according to its code, and its signals are received at Y as will be apparent from Fig. 4. 60 Similarly, a box pulled at the other side of break c signals over recorder Z. If several boxes are pulled on the same side of the break, there is no non-interference action and the signals received at X or Y will be mingled. However, if two boxes 65 are pulled on different sides of the break, both send comprehensible signals, the signal of 101 being, for example, received at Y over circuit e and the signal of 104 over circuit f at recorder Z.

Assuming now an accidentally grounded signal loop as indicated at g in Fig. 5, the direct current recorder or relay X remains energized, since the direct current circuit h is not interrupted, but alternating current circuits i and k now being established in addition, recorders Y and Z are also 75

energized and attracted, indicating the faulty condition of the circuit. Since the direct current circuit is normal, correct signals are received at X from all boxes just as if ground g was not present.

If a short circuit exists across a signal box, for example, around box 102 as indicated at m in Fig. 3, this box is not able to signal over the direct current circuit since it is by-passed with respect thereto, but its signals are correctly received at recorders Y and Z , since upon becoming deenergized, the boxes of type N , P , R , and S drop the armatures of their exclusively direct current responsive non-interference magnets and signal through ground over circuits a and b of Fig. 3. Boxes of type M also signal through ground, as will be obvious from Fig. 1. The remaining unshunted boxes are not influenced by the short circuit around box 102 and send their signals in normal manner. If boxes of type M and P are used and, for example, box 101 and short circuited box 102 are pulled simultaneously, the signals of 102 are lost since 101 signals normally over ground, so that the signals become mingled at the alternating current recorders. With boxes of types N , R and S , however, which do not normally connect the loop to ground, both boxes 101 and 102 , if simultaneously pulled, transmit understandable signals, box 101 over relay X and box 102 over the alternating current recorders.

A short circuit across the entire signaling loop, as indicated at n of Fig. 3, influences a circuit according to my new system as follows. Any one of the short circuited boxes is able to send signals over ground, which signals are received at X and/or Y . However, under this condition, two or more simultaneously pulled boxes produce mixed signals since the non-interference mechanisms of all short circuited boxes are incapacitated upon being deprived of their energizing direct current.

The modification according to Fig. 2, of which Fig. 6 is a simplified diagram, carries under normal conditions, direct as well as alternating currents because the secondary 52 of transformer Q applies normally an E. M. F. to circuit A . Recorders V and W are therefore normally energized like the direct current recorder X , and upon operation of any box correct signals are received at X , V and W , provided the circuit is in normal condition. Recorder U , however, is normally deenergized, since no current flows from the transformer to ground, so long as the signal loop is ungrounded. In case two or more boxes operate simultaneously, the non-interference devices thereof operate in the normal manner and correct signals are received at recorder X .

In the case of a broken circuit, as indicated at c of Fig. 7, the direct current circuit is interrupted, the non-interference magnets of the boxes deenergized, and box 102 for example, if pulled, operates through ground and alternating current circuit p as indicated in Fig. 7. The signals of box 102 are therefore received correctly at recorders V and U . Similarly, a box at the other side of the break, for instance, box 104 , signals over circuit q and its signals are received at W and U . In case both boxes 102 and 104 should be operated simultaneously, their signals are correctly received at V and W respectively, (whereas they are mingled at U) in spite of the fact that the non-interference magnets of all boxes are incapacitated by the break.

Assuming now that the signal circuit is ground-
ed, as indicated at r of Fig. 8, the direct current

circuit s is not disturbed and all boxes operate correctly and with all their non-interference features, the signals being recorded at X . In addition, recorder U is energized by the alternating current flowing from the line ground to terminal 40 of the transformer indicating the faulty condition of the line.

If a short circuit exists around a signal box as, for example, short circuit t around box 102 of Fig. 6, this box is excluded from the direct current circuit, whereas the normal direct current operation of X , by the other boxes, remains intact. The non-interference magnet of box 102 grounds the box as indicated with dotted lines in Fig. 6 and the box signals over circuit u , the signals being received correctly at U . The alternating current signals could not be received at V or W , since these recorders are continuously energized so long as there is no break in the signal circuit. In case a short circuited box, as for instance box 102 , and another box, as for example box 104 are operating simultaneously, the signals of box 104 are correctly received at X and the signals of 102 at U .

If the entire signal loop is shunted out, as indicated at v of Fig. 6, signals from any one box will be received correctly at the alternating current relay U , as will now be apparent from the foregoing description, whereas signals from any simultaneously pulled boxes can not be correctly received under these extremely unfavorable circumstances.

From the foregoing description of the operation of my new signaling system during the existence of the principal forms of faulty circuit conditions, for various types of boxes, its emergency operation during disturbances caused by combinations of these principal faults can be deduced without further detailed explanations.

In certain instances it may be desirable to employ alternating current for normal signaling, and direct current for emergency transmission. For this purpose, my new system can be modified according to Fig. 9. In this figure, L is again the outside loop or signaling circuit, A is an alternating current supply and reception circuit, and D a direct current supply and reception circuit. The loop comprises signal transmitters indicated as alarm boxes 106 and 107 and is connected to station terminals 111 and 112 . The alternating current circuit A comprises a transformer O with primary 151 connected to a suitable alternating current source, preferably the public utility line and a secondary 152 , a recorder or relay 115 and condensers 116 and 117 and is connected to the other circuits at 111 and 112 . The direct current circuit D , also connected across terminals 111 and 112 , comprises a battery 140 having one terminal grounded, whereas the other terminal is connected to a recorder 121 . In series across 111 and 112 are two choke coils 124 and 125 and two recorders 122 and 123 , the second terminal of recorder 121 being connected intermediate 122 and 123 . From the preceding explanation, it will be apparent that, under normal conditions of the line, signals are received at 115 , whereas the direct current circuit is deenergized if the line is not grounded. When the loop is interrupted, for example, at y , the alternating current circuit is interrupted, but signals can be despatched over ground and one of receivers 122 , 123 , depending on which side of the break the signaling box is located. The operation of this modification under other faulty conditions will be apparent from the preceding detailed description of the modifica-

tions with emergency alternating current, and direct current for normal operation.

The new system is especially well adapted for use with simple and reliable provisions for a reserve power supply, as will now be explained with reference to Fig. 10, which shows an arrangement comprising several signal loops. This installation has an alternating current supply indicated by busses AC, and two outer circuits or loops L which are associated with direct current supply circuits D and alternating current supply circuits A. The circuits L, D and A are similar to corresponding arrangements of Figs. 1 and 2, corresponding elements being identified with like numerals, and need therefore no further explanation. Instead of recorders, relay magnets E are shown, which may for example be associated with suitable repeater circuits. The outer circuits L include signal transmitters 110, 120, 130 and also signal receiving stations as, for example, fire-houses, as indicated by bells F. The circuits D are supplied from busses AC through rectifier bridges K whereas circuits A are supplied from busses 131 through transformers 132, busses AC and 131 being connected by a normally closed switch 161. A reserve battery RB, maintained in charged condition by any suitable arrangement known for that purpose, is adapted to supply current to the motor 168 of an inverter I through normally open switch 162. The generator 169 of the inverter is connected to busses 131 through normally open switch 163. Switches 161, 162 and 163 are operated by magnets 171, 172 and 173 respectively, which are normally energized from busses AC. Switch 161 remains closed, and switches 162 and 163 are open, so long as busses AC supply the installation, for example, from the public utility system. When the alternating current fails, switch 161 opens, and switches 162 and 163 close. Battery RB starts the inverter which now supplies busses 131 with alternating current similar to that normally flowing in busses AC. The direct current circuits D are then energized by floating batteries B, and busses AC and 131 are separated by open switch 161, so that the inverter can not feed energy into the alternating current supply system. Upon the return of the normal current supply, the inverter is again separated from the battery and alternating current supply by switches 162 and 163, and busses AC and 131 are connected by switch 161.

It should be understood that the present disclosure is for the purpose of illustration only and that this invention includes all modifications and equivalents which fall within the scope of the appended claims.

I claim:

1. A signaling system comprising a normally closed signal circuit with signal senders and conductive for alternating and direct currents, said senders having means for signaling through ground, means for supplying direct current to said circuit, an alternating current source connected with one terminal to said circuit and with the other terminal to ground, and an alternating current signal receiver in series with said source separate from said circuit, said alternating current source normally applying an alternating electromotive force to ground and said circuit and forming with said alternating current receiver an auxiliary circuit including said senders but exclusive of said direct current supply.

2. A signaling system comprising a normally closed signal circuit with signal senders and conductive for alternating and direct currents, said

senders having means for signaling through ground, means for supplying direct current to said circuit, an alternating current signal receiver and a grounded alternating current source connected in series with said alternating current receiver with its terminals across said circuit, said alternating current source normally feeding alternating current to said circuit through said terminals, and in addition through ground if said circuit is grounded.

3. A signaling system comprising a normally closed signal circuit with signal senders and conductive for alternating and direct currents, said senders having means for signaling through ground, a direct current source normally supplying said circuit, a conductor including a signal recorder across said circuit forming an auxiliary signaling circuit and including said senders, means for excluding direct current from said conductor and an independent alternating current source connected between said conductor and ground, for supplying said auxiliary circuit with alternating current upon grounding thereof.

4. A signaling system comprising a signaling loop, means for supplying from a normal preferred power source direct current to said loop and means for supplying thereto alternating current superposed upon said direct current, a normally disconnected reserve power supply, and means for energizing said second supply means from said reserve power supply, upon failure of said normal source.

5. A signaling system comprising a signaling loop, a preferred normal source of alternating current, an emergency source of direct current, means including a unidirectional conductor for supplying unidirectional electromotive force from said normal source to said loop, means including a normally closed switch for supplying alternating electromotive force from said normal source to said loop simultaneously with said unidirectional electromotive force, means for converting the direct current supply of said emergency source to emergency alternating electromotive force substantially similar to the alternating electromotive force of said normal source and means for supplying said emergency alternating electromotive force to said loop, and for opening said switch upon failure of said normal source.

6. A signaling system comprising a signal loop with signal senders in series therein, an emergency conductor which may be connected to portions of said loop for signal transmission therethrough, a circuit supplying direct current to said loop and said senders, a second circuit supplying alternating current to said loop and said senders and connected to said emergency conductor, signal manifesting means in each of said circuits for direct reception from said senders, and means for excluding alternating current from said first circuit and for excluding direct current from said second circuit.

7. A signaling system comprising a normally closed signal loop carrying direct current and including signal senders and direct current signal receiving means, an emergency conductor which may be connected to portions of said loop for signal transmission therethrough, an auxiliary conductor exclusive of said direct current receiving means, having alternating current receiving means associated therewith, and including portions of said emergency conductor, and means for supplying alternating current to an auxiliary circuit including for effective signaling at least part of said signal senders and formed by said

auxiliary conductor and part of said signaling loop.

8. A signaling system comprising a normally closed signal loop including signal senders, an emergency conductor which may be connected to portions of said loop for signal transmission therethrough, a source supplying direct current to said loop and said senders, an alternating current signal receiver, an auxiliary circuit exclusive 5 of said direct current source associated with said signal loop, said emergency conductor and said alternating current receiver for transmitting signals from said senders, and an independent source supplying alternating current to said auxiliary circuit through said emergency conductor, said alternating current receiver and said independent source being located in a portion of said auxiliary circuit which carries only alternating current.
9. A signaling system comprising a normally closed signal loop including signal senders and receivers and carrying direct current, an emergency conductor which may be connected to portions of said loop for signal transmission therethrough, an auxiliary conductor adapted to be associated with said signal loop to form a circuit exclusive of said receivers but including said emergency conductor and at least one of said senders to transmit signals therefrom, an alternating current receiver 25 and an alternating current source associated with said circuit and said conductor, said source normally superposing alternating current upon said direct current and supplying alternating current to said conductor if the latter is through said emergency conductor associated with said loop.
10. A signaling system comprising a normally closed signal loop carrying direct current and including signal senders capable of signaling through ground, and an independent alternating current circuit including a receiver and an alternating current source connected across, and normally supplying said loop, said alternating current source being grounded at a point dividing the voltage of said source.
11. A signaling system comprising a normally closed signal loop conductive for direct and alternating currents, serially including signal transmitting devices capable of signaling through ground and having two terminals, a direct current source, a signal recorder and an inductance serially connected across said terminals, an alternating current circuit including grounded alternating current supply means and a signal recorder connected to said terminals in parallel to said loop, and means for excluding direct current from said alternating current circuit, said inductance substantially excluding alternating current from said direct current recorder.
12. A signaling system comprising a normally closed signal loop conductive for direct and alternating currents, serially including signal transmitting devices capable of signaling through ground and having two terminals, a direct cur-

rent source, a signal recorder and an inductance serially connected across said terminals, and an alternating current source and a signal recorder connected across said terminals through capacitances, a point of said alternating current source 5 being grounded.

13. A signaling system comprising a normally closed signal loop conductive for direct and alternating currents, serially including signal transmitting devices capable of signaling through ground and having two terminals, a direct current source, a signal recorder and an inductance serially connected across said terminals, two capacitances and a signal recorder therebetween serially connected across said terminals, and an 15 alternating current source having one terminal grounded and the other terminal connected intermediate said capacitances.

14. A signaling system comprising a normally closed signal loop conductive for direct and alternating currents and including signal transmitters, an emergency conductor which may be connected to portions of said loop for signal transmission therethrough, an alternating current supply and signal reception circuit connected to 20 said loop and said emergency conductor and normally applying an alternating electromotive force thereto, a direct current supply and signal reception circuit connected to said loop in parallel with said alternating current circuit, means in said 25 alternating current circuit substantially excluding direct current therefrom, and means in said direct current circuit substantially excluding alternating current therefrom.

15. A signaling system comprising a signal loop 35 with signal senders in series therein, an emergency conductor which may be connected to portions of said loop for signal transmission therethrough, a circuit supplying direct current to said loop and said senders, a signal manifesting means in said 40 circuit, a second circuit supplying alternating current to said loop and said emergency conductor, said second circuit being connected between a point of said loop and a point of said emergency conductor and including in series a transformer 45 and a signal manifesting means, and means for excluding alternating current from said first circuit and for excluding direct current from said second circuit.

16. A signaling system comprising a normally 50 closed signal loop conductive for direct and alternating currents, serially including signal transmitting devices capable of signaling through ground and having two terminals, a direct current source, a signal recorder and an inductance 55 serially connected across said terminals, two capacitances serially connected across said terminals, an alternating current source having one terminal grounded and the other terminal connected intermediate said capacitances, and a signal recorder connected in series to said alternating current source and one of said capacitances between ground and one of said terminals.

FRANK R. BRIDGES.

CERTIFICATE OF CORRECTION.

October 6, 1936.

Patent No. 2,056,709.

FRANK R. BRIDGES.

It is hereby certified that error appears in the printed specification of the above numbered patent requiring correction as follows: Page 6, first column, line 68, claim 1, for "on" read an; and that the said Letters Patent should be read with this correction therein that the same may conform to the record of the case in the Patent Office.

Signed and sealed this 29th day of December A. D. 1936.

(Seal)

Henry Van Arsdale
Acting Commissioner of Patents.
